UNITED STATES PATENT OFFICE

171,665

CHRISTMAS GIFT STOCKING

Anna Satey, Detroit, Mich., assignor of one-fourth to Olga Hall, Hamtramck, one-fourth to Mary Blair, Detroit, and one-fourth to Mary Flowers, Hamtramck, Mich.

Application November 1, 1950, Serial No. 12,803

Term of patent 14 years

(Cl. D47—7)

To all whom it may concern:

Be it known that I, Anna Satey, a citizen of the United States and a resident of the city of Detroit, county of Wayne, State of Michigan, have invented a new, original, and ornamental Design for a Christmas Gift Stocking, of which the following is a specification, reference being had to the accompanying drawing, in which:

Fig. 1 is a side elevational view of a Christmas gift stocking showing my new design;

Fig. 2 is a front view of said Christmas gift stocking.

I claim:

The ornamental design for a Christmas gift stocking, as shown.

ANNA SATEY.
